BY HIS ATTORNEYS

William D. Meacham

UNITED STATES PATENT OFFICE.

CHRIST SIEVERT, OF CALIO, NORTH DAKOTA.

HARNESS HANGER.

Application filed August 20, 1920. Serial No. 404,880.

To all whom it may concern:

Be it known that I, CHRIST SIEVERT, a citizen of the United States, residing at Calio, in the county of Cavalier and State of North Dakota, have invented certain new and useful Improvements in Harness Hangers; and I do hereby declare the following to be a full, clear, and exact description of the invention, such as will enable others skilled 10 in the art to which it appertains to make and use the same.

The object of my invention is to provide a very simple and efficient harness hook and hanger which may be manufactured at little 15 cost and which provides for the vertical elevation and the supporting means thereof of said harness.

Generally stated, my invention consists of the novel devices and combinations of devices hereinafter described and defined in 20 the claims.

In the accompanying drawings, like notations refer to like parts throughout the several views.

25 Referring to the drawings:—

Fig. 1 is a side elevation of my improved harness hanger showing its lowered position in dotted lines;

Fig. 2 is a front elevation of the same;

30 Fig. 3 is an enlarged section taken through the line 3—3 of Fig. 2, with some parts detached; and

Fig. 4 is a fragmentary detail view, on an enlarged scale, of my sliding block 35 detached.

The numeral 5 indicates an ordinary post having a vertically slotted guideway 6 bolted to it some distance from the floor and extending to its top. Within this guideway 6, fits a reciprocally shaped sliding block 7 (best shown in Fig. 3) capable of vertical movement. A carrier bracket 8, having a hook 9 for the bridle and a hanger 10, is securely fastened at both of its arms 40 to said sliding block 7.

Fastened to a small bent portion 10^a in the upper hanger arm 10 of the carrying bracket 8 next to the block, is a cable 11 which goes through a pulley 12 bolted to or 45 near the top of said post.

The sliding block 7 has ratchet notches 7^a on one of its edges, which are engaged by the pawl end of a dog 13 pivoted on the post 5, capable of holding said block in various desired positions in the guideway 6.

Said dog 13 has a hole 14 near its upper

end through which an end link of a trip chain 15 is fastened. The other end link of said trip chain 15 encircles the bight of the cable 11, so that, when said cable is 60 pulled downward from a slight angle, the tension thereby caused on the trip chain 15 will be sufficient to pull back the pivoted dog, disengaging its pawl and so release the sliding block 6 carrying said hanging 65 bracket 8.

To limit the downward vertical movement of my block, I provide an angular stop 16 bolted to the said post near the floor.

The operation of my invention thus described is probably obvious. When the harness is taken off the horse, my hanger is lowered, when tension is put on the trip chain 14 by pulling the cable 11 from an angle. This allows the block and bracket 70 75 to slide down and, when sufficiently low, the angular tension on said cable is released and again the dog engages a ratchet notch on the block and is held securely. The stop 16 limits the downward movement of said block 80 and keeps it from leaving its guideway 6.

The heavy harness is then hung on the bracket 8 and carrying bar 10 and raised out of the way by a downward pull on the cable 11 fastened to the block end of the bracket 85 arm 10. This is facilitated by said overhead pulley 12. When the said harness is sufficiently elevated, the cable is released and the dog 13 again engages a notch in said block. 90

The simplicity of my invention and its inexpensiveness of manufacture, as well as its high efficiency, should be now clearly discernible.

What I claim is:—

1. A harness hanger having in combination a vertical guideway, a member slidable therein carrying a harness hook, a pivoted lever dog adjacent said guideway and adapted to contact with said member at various points to hold the same in position, an overhead pulley, a cable secured to said member and passing over said pulley and forming an elevating means for said member, and a flexible connection between said cable and said lever dog. 95 100

2. A harness hanger having in combination a vertically movable member comprising a harness hook, a pivoted means adjacent said member adapted to engage the same to hold said member in position, a pulley disposed above said member, a cable 110

2
disposed over the pulley and adapted to be pulled to elevate said member, and a flexible means connected to said pivoted means through which the cable passes.

- 5 3. A harness hanger having in combination a vertical guideway, a ratchet bar carrying a harness hook slidable therein, a dog pivoted adjacent said guideway engageable with said ratchet bar to hold the same in 10 the desired position, a pulley at the top of said guideway, a cable connected to said member and passing over said pulley adapted to be pulled to elevate said member, a flexible member connected to said dog 15 through which the cable passes whereby the dog can be engaged and disengaged by movement of said cable.

4. A harness hook having in combination,

a member comprising a harness hook guided for vertical movement, pivoted means 20 adapted to engage said member at different points to hold the same in position, a pulley disposed above said member, a cable secured to said member and passing over said pulley and forming an elevating means for said member, and means connected to said pivoted means and engaging said cable whereby the said pivoted means can be operated to engage and disengage said member by 25 means of said cable.

In testimony whereof I affix my signature in presence of two witnesses.

CHRIST SIEVERT.
